Term of patent 14 years

Int. Cl. D22—05

U.S. Cl. D22—26

FIG. 1 is a top plan view of a combination ice fishing jig stick and reel embodying our new design;

FIG. 2 is a side elevational view thereof;

FIG. 3 is a bottom plan view thereof;

FIG. 4 is a side elevational view thereof from a side opposite from FIG. 2;

FIG. 5 is a sectional view thereof taken on line 5-5 in FIG. 2;

FIG. 6 is an end view thereof looking at the handle end; and

FIG. 7 is an end view thereof from an end opposite from FIG. 6.

This application is a continuation-in-part of our co-pending design patent application Ser. No. 180,246, filed Sept. 13, 1971, for Ice Fishing Jig Stick and Reel, now abandoned.

We claim:

The ornamental design for a combination ice fishing jig stick and reel, as shown.
